No. 829,137.

PATENTED AUG. 21, 1906.

J. BRAUCHLI.
T AND ANGLE SQUARE.
APPLICATION FILED DEC. 7, 1905.

UNITED STATES PATENT OFFICE.

JACOB BRAUCHLI, OF HAMPTON, VIRGINIA.

T AND ANGLE SQUARE.

No. 829,137.

Specification of Letters Patent.

Patented Aug. 21, 1906.

Application filed December 7, 1905. Serial No. 290,789.

To all whom it may concern:

Be it known that I, JACOB BRAUCHLI, a citizen of the United States, residing at Hampton, in the county of Elizabeth City 5 and State of Virginia, have invented certain new and useful Improvements in T and Angle Squares, of which the following is a specification.

Measuring instruments of the type for laying off angles and embodying two legs have a limited application as generally constructed. It is the purpose of this invention to devise a T and angle square of novel structure, being designed more especially as an improvement 15 on the instrument for which Letters Patent of the United States were granted to me January 6, 1903, No. 717,534.

The purpose of the invention is to supply a T-square which can be used with either side 20 resting upon the surface, thereby enabling the laying off of any angle and the complement of said angle by simply reversing the instrument, the straight-edge of the head being placed against a shoulder or the edge of a 25 table or board or made to coincide with a right line in each position of the square.

A further purpose of the invention is to combine with the head of a T-square stops for leveling the instrument and to provide 30 abutments to engage with a shoulder or the edge of a table or drawing-board when the square is used in reversed position, said stops being adjustable transversely or at a right angle to the plane of the instrument and directed in their several adjustments by suitable 35 guides and adapted to be secured in the required position, according to the particular use of the square.

The invention also contemplates other improvements, which will appear from the appended description and the accompanying drawings, in which corresponding and like parts are referred to and indicated by the same reference characters.

For a full description of the invention and the merits thereof and also to acquire a knowledge of the details of construction of the means for effecting the result reference is to be had to the following description and accompanying drawings.

While the invention may be adapted to different forms and conditions by changes in the structure and minor details without departing from the spirit or essential features 55 thereof, still the preferred embodiment is

shown in the accompanying drawings, in which—

Figure 1 is a top plan view of a T-square embodying the invention. Fig. 2 is a longitudinal section on the line x x of Fig. 1. Fig. 3 is an edge view of the head. Fig. 4 is a transverse section on the line y y of Fig. 1, showing the parts on a larger scale. Fig. 5 is a detail view showing more clearly the means for preventing turning of the fastening when tightening the same to secure the movable blade in an adjusted position. Fig. 6 is a detail view of the outer edge portion of the arc, showing the graduations thereon and the pointer coöperating therewith to properly 70 position the blade.

The instrument comprises a head 1 and a blade 2, the latter having pivotal connection with the head, so as to be adjusted to any desired angle. The head comprises a straight-edge 3 and an arc 4, which may be graduated in any accustomed way to admit of the instrument being used as a protractor, if so desired, or the blade 2 moved to any of the usual angles and secured in any adjusted position by ready fastening means, which in the present instance consist of a spring-tongue 5, having a projection 6 and a series of openings or recesses 7, formed in the side of the part 4 adjacent to the tongue 5 to receive the projection 6. The openings or recesses 7 are located upon the arc at points corresponding with the usual angles—thirty degrees, forty-five degrees, sixty degrees, and ninety degrees. When it is required to adjust the 80 movable blade 2 to any of the usual angles, the free end of the spring-tongue 5 is moved away from the arc a distance to withdraw the projection 6 from engagement with any of the openings or recesses 7, and after the blade 95 has reached the desired position it is held fast by entrance of the projection 6 into the corresponding opening or recess 7. When it is required to adjust the blade to any angular position intermediate or beyond the 100 usual angles, it is necessary to have recourse to other securing means for fastening the blade in the adjusted position. For this purpose a post 8 and thumb-nut 9 are provided, said post also serving as a means for pivotally connecting the blade to the head. The head of the post 8 is beveled and let into the blade, so as to come flush therewith, and by preference a sleeve 10 is mounted upon the post 105 and is fitted into an opening in a boss or hub 110

of the head, said sleeve having the end adjacent to the blade enlarged and beveled. To prevent turning of the post when tightening the thumb-nut 9 thereon, a portion 11 thereof at the base of the threaded end is flattened to snugly fit within an elongated opening 12 of a washer 13, the latter having a tongue 14 fitted into a recess 15 at one side of the opening, in which the sleeve 10 and washer 13 are fitted. The arc 4 may be graduated in any manner to admit of the desired angle being readily determined, and by preference the said graduations are formed on the outer edge of the arc, and a pointer or indicator 16 co-operates therewith and is attached to the projecting end of the spring-tongue 5.

It will be noticed that the upper side of the blade 2 is unobstructed. Hence, when required, the instrument may be reversed and placed upon the work with the head occupying the uppermost position. To prevent rocking of the instrument, stops 17 are fitted to the projecting ends of the straight-edge 3, said stops being adjustable transversely of the head or in a direction at a right angle to the plane of the instrument. The stops may be adjusted to have the ends on the same side with the blade 2 terminate in a plane touching the face of said blade, with the result that, the instrument when placed upon a plain surface is prevented from any rocking movement. The stops may also be adjusted to project beyond the plane of the blade 2, so as to engage with a shoulder or the edge of a drawing-board or table to properly position the instrument when used in this capacity for marking right lines from a given edge or shoulder against which the head is usually placed to determine the relative position of the blade 2. The adjustment of the stops is of advantage in that it provides for regulating the degree of projection according to the depth of the shoulder against which the head may be placed. The stops are adjustable in right lines and are directed in their movements by suitable guides, which in the present instance are formed by recesses 18, formed in the straight-edge of the head. Transverse slots 19 are provided and in the straight-edge of the head to receive the fastening-bolts 20, by means of which the stops 17 are held in place, and which also provide for movement of the fastening 20 incident to adjustment of the stops. The fastenings 20 consist of screws upon the threaded ends of which are mounted thumb-nuts 21, the straight-edge being clamped between the thumb-nuts and the stops when the latter are made fast. Lateral offsets 22 are provided at one end of the stops 17 and overlap the straight-edge 3 and limit the movement of the stops in one direction. The offsets 22 perform the dual office of rests and stops to fix the position of the parts 17. When the stops 17 are moved to cause the inner edges

of the offsets 22 to come in contact with the straight-edge 3, the outer ends of said stops and parts 22 touch a plane parallel with the top face of the blade 2 and in contact therewith. Hence when placing the instrument upon a plane with the face of the blade 2 in contact with said plane the stops and offsets 22 likewise touch said plane and fix the position of the instrument and prevent any rocking movement thereof. The offsets 22 engage with the straight-edge 3 on the side opposite to that provided with the slots 19. Hence should the fastenings 20 be loose there is no likelihood of the stops becoming displaced or lost, since the offsets 22 prevent movement of the stops in one direction and the fastenings 20 limit their movement in the opposite direction. The stops 17 are let into the straight-edge 3 so as to come flush with the outer face thereof, thereby preventing any interference with the ordinary use of the instrument.

It will be understood from the foregoing that the instrument may be used with either face or side uppermost, which is of material advantage in an instrument of the character aforesaid. It will be further noticed that the movable blade may be adjusted to any of the usual angles or to any intermediate or exterior position thereof and the reversibility of the square provides for accurately drawing a line at any angle and a second line the complement thereof, the two complementary angular positions being obtained by the obverse and reverse position of the instrument with reference to the work, as will be readily comprehended.

Having thus described the invention, what is claimed as new is—

1. In a measuring instrument of the character specified and in combination with the head and blade, adjustable stops applied to the head upon each side of the blade to be projected from a side thereof to a greater or less extent to steady and enable proper adjustment of the instrument to the work, substantially as set forth. 105

2. In a measuring instrument of the character substantially as set forth, the combination with the head and blade, of a stop applied to the head and arranged a distance from the blade and adjustable transversely or at a right angle to the plane of the instrument, and means for securing the said stop to the head in an adjusted position. 115

3. In a measuring instrument of the character substantially as set forth, and in combination with the head and blade, of a stop adjustable transversely of the head and having a lateral offset to engage with said head 125 and properly position the stop and limit its movement in one direction, and means for securing the stop to the head and limiting its movement in the opposite direction.

4. In a measuring instrument of the char- 130

- acter specified, the combination with the head and blade, the head having a slot extended inward from one edge, a stop adjustable transversely of the head and having a lateral offset to engage with the side of the head opposite to that provided with the slot, and a fastening for securing the stop to the head in an adjusted position and passed through the said slot thereof.
- 10 5. In an instrument of the character set forth, the combination of a head, a blade projected therefrom, said head having transverse

slots, stops laid into the straight-edge of said head and provided with lateral offsets to engage with the side thereof opposite to that provided with the slots, and fastenings for securing the stops to the head in an adjusted position.

In testimony whereof I affix my signature in presence of two witnesses.

JACOB BRAUCHLI. [L. S.]
